[57] **CLAIM**

The ornamental design for a combined padlock and removable electronic key, as shown.

DESCRIPTION

FIG. 1 is a front elevational view of a combined padlock and removable electronic key showing my new design therefor;

FIG. 2 is a rear elevational view;

FIG. 3 is a top plan view;

FIG. 4 is a bottom plan view;

FIG. 5 is a left side elevational view;

FIG. 6 is a right side elevational view.

FIG. 7 is a front elevational view of the padlock with the electronic key removed to better illustrate the design features of the points of connection;

FIG. 8 is a rear elevational view;

FIG. 9 is a top plan view;

FIG. 10 is a bottom plan view;

FIG. 11 is a left side elevational view; and,

FIG. 12 is a rear elevational view of the electronic key removed from the padlock to better illustrate the design features of the points of connection, all other views of the electronic key being the same shown in FIGS. 1 through 6.
